CUSTOMER STATION FOR A DRIVE-IN BANK SYSTEM

John F. Carson, % Midwest Bank Builders Inc.,
5666 W. 95th St., Oak Lawn, Ill.

Filed Aug. 10, 1964, Ser. No. 81,228

Term of patent 14 years

(Cl. D13—1)

Fig. 3

Fig. 2

Fig. 1

FIGURE 1 is a side view of the customer station for a drive-in bank system;

FIGURE 2 is a front elevation view of the customer station for a drive-in bank system with the door enclosure open;

FIGURE 3 is a front elevation view of the customer station for a drive-in bank system with the door enclosure closed.

I claim:

The ornamental design for the customer station for a drive-in bank system, substantially as shown.
